Robert Holden,

INVENTOR,

BY *W. Brewerton,*

His ATTORNEY.

UNITED STATES PATENT OFFICE.

ROBERT GOLDEN, OF BROOKLYN, NEW YORK.

CLASP FOR DOCUMENTS, &c.

1,401,770.

Specification of Letters Patent. Patented Dec. 27, 1921.

Application filed November 4, 1921. Serial No. 512,755.

To all whom it may concern:

Be it known that I, ROBERT GOLDEN, a citizen of the United States, and a resident of the borough of Brooklyn, county of 5 Kings, and State of New York, have invented a new and useful Improvement in Clasps for Documents, &c., of which the following is a specification.

This invention relates to improvements in 10 clips or clasps for documents, business cards, etc., and has for its particular objects the provision of a simple, inexpensive yet effective device for use in connection with dictating machines such for example as are commonly known as Ediphones or Dictaphones.

I am aware that various spring clasps 15 have been devised for holding papers, business cards and other documents, but none of them are capable of use on the container of 20 a dictating or talking machine record in the manner hereinafter described for employing my improved clasp.

In the accompanying drawings in which is illustrated a preferred embodiment of my 25 improved clasp,

Figure 1 is a front elevation.

Fig. 2 a side elevation of such clasp in position on a cylindrical record container, and 30 Fig. 3 a perspective view of such clasp, isolated.

Referring to the drawings and the construction shown therein, the reference numeral 1 designates a longitudinal metallic base member, the same having a reduced 35 neck-portion 2 which terminates in a duck-bill head 3. Oppositely extending arms 4, 4' are formed integral with said base member, the former being provided with a hook 5 and the latter having a hook or like device 40 6 for connecting a flexible strap-member thereto. Said strap-member comprises a chain 7, preferably having oblong links, to which is secured a coil-spring 8 the terminal ring or loop 9 of which is adapted to fit 45 over said hook 5 and hold the device on a container in the position shown in Fig. 1. Said flexible strap is of course shorter, for example one-half inch shorter, than the gap 50 along the periphery of a record container which exists between the opposing free ends 55 of arms 4, 4'. Suitable barbs 10 are formed at intervals on the arms and base-member in order to prevent accidental displacement of the clasp when applied to a record container, such as A for example.

A clip-member which is arched at one

end 11 and upturned at the other end 12 is pivotally secured to said base-member by means of a V-shaped leaf spring-member 13 that projects through apertures a, a' and b, 60 in the base and clip-members respectively and has inturned or upset ends 14, 14'. In-turned lugs 15 coöperate with said barbs 10 in preventing displacement of the clasp when in use. An indicator card holder 16 is 65 formed on the clip-member adjacent the aperture b therein and the same serves to receive an identification card of any desired color or bearing any desired symbol or legend. 70

This clasp is not only useful for holding letters and other documents on the top of the record container while dictating therefrom into the receiver horn of the dictating machine, but after the record is placed in the 75 container the clasp may be advantageously used to hold the copy used in such dictation in order that the typists may have the same for ready reference during the reproduction of such record. 80

Various modifications, within the scope of the appended claims, may be made without departing from the spirit of my invention as herein set forth. For example the hook 5 may be crimped on the end 9 of said coil 85 spring to permanently hold the said flexible strap and thus facilitate the adjustment of the proper link of chain 7 over the hook 6, since obviously, where the container to which the clasp is to be applied is smaller 90 than that for which the flexible strap is normally intended, then one of the intermediate links and not the terminal link will be hooked to hook 6.

Having thus described my invention what 95 I claim and desire to secure by U. S. Letters Patent is:

1. In a clasp for record containers, the combination comprising a base-member having oppositely disposed arms rigidly connected thereto and projecting therefrom, an elastic strap-member adapted to elastically connect the free ends of said arms and securely hold said clasp in any adjusted position on the outer surface of a container and 100 a movable clip-member, for retaining documents, movably secured to said base-member intermediate said arms. 105

2. In a clasp for record containers, the combination comprising a base-member having oppositely disposed arms rigidly connected thereto and projecting therefrom, an 110

elastic means comprising chain and spring members adapted to elastically connect the free ends of said arms and securely hold said clasp in any adjusted position on the outer surface of a container and a movable clip-member, for retaining documents, movably secured to said base member intermediate said arms.

3. In a clasp for record containers, the combination comprising a base member having oppositely disposed arms rigidly connected thereto and projecting therefrom, an elastic strap-member adapted to elastically connect the free ends of said arms and securely hold said clasp in any adjusted position on the outer surface of a container, a movable clip-member, for retaining documents, movably secured to said base-member intermediate said arms, and means projecting inwardly from said arms for preventing

accidental displacement of said clasp when in any adjusted position on a container.

4. In a clasp for record containers, the combination comprising a base-member having oppositely disposed arms rigidly connected thereto and projecting therefrom, an elastic strap-member adapted to elastically connect the free ends of said arms and securely hold said clasp in any adjusted position on the outer surface of a container, a movable clip-member, for retaining documents, movably secured to said base-member intermediate said arms and barbs formed on said arms for preventing accidental displacement of said clip.

Signed at New York city, in the county of New York and State of New York, this 3rd day of November, 1921.

ROBERT GOLDEN.
